(57) **CLAIM**

The ornamental design for a bullet battery camera, as shown and described.

DESCRIPTION

FIG. 1 is a perspective view of a bullet battery camera design showing our new design.

FIG. 2 is a front view of a bullet battery camera.

FIG. 3 is a rear view of a bullet battery camera.

FIG. 4 is a left side view of a bullet battery camera.

FIG. 5 is a right side view of a bullet battery camera.

FIG. 6 is a top view of a bullet battery camera.

FIG. 7 is a bottom view of a bullet battery camera; and, FIG. 8 is a rear, bottom side perspective view of a bullet battery camera.

Any shading and cross-hatching are not features of the design but are utilized to illustrate the surface contours of the bullet battery camera design in the drawings.
